UNITED STATES PATENT OFFICE.

FRANK SCHLATTAU, OF LOS ANGELES, CALIFORNIA.

SAFETY-RAZOR.

1,210,216.

Specification of Letters Patent. Patented Dec. 26, 1916.

Application filed January 4, 1916. Serial No. 70,191.

To all whom it may concern:

Be it known that I, FRANK SCHLATTAU, a citizen of the United States, residing at Los Angeles, in the county of Los Angeles and 6 State of California, have invented certain new and useful Improvements in Safety-Razors, of which the following is a specification.

This invention relates to safety razors and 10 has as its object to provide an article of this class so constructed that the same may be employed in the same manner as the ordinary safety razor; that is to say, with the blade presented at right angles to the handle 15 and transversely thereof, and may also be employed in substantially the same manner as the ordinary razor.

Another aim of the invention is to provide a novel construction of head and cap plate 20 in a razor of this type adapting the same for use with thin double-edged flexible blades, the construction being such that the blade will be flexed to the desired curve and consequently held in adjusted position.

25 Another aim of the invention is to provide a novel means for the assemblage and connection of the cap plate with the head of the razor, which means will serve to definitely position the cap plate with relation to 30 the head and to the blade confined between the two.

In the accompanying drawings: Figure 1 is a perspective view of the razor embodying the present invention, the handle being 35 shown in full lines in one position in which it may be assembled with the head of the razor and in dotted lines in another position in which it may be assembled. Fig. 2 is a vertical longitudinal sectional view through 40 the razor, the handle being shown in elevation. Fig. 3 is a vertical transverse sectional view therethrough. Fig. 4 is a bottom plan view of the blade holding head and cap plate assembled. Fig. 5 is a perspective 45 view of the cap plate removed.

In the accompanying drawings the head of the razor is indicated in general by the numeral 1 and comprises a body which is approximately rectangular in general outline 50 and is provided with a convex upper face indicated by the numeral 2, the said face being curved continuously between the longitudinal edges of the said body. In its under face the body 1 is formed with a threaded 55 socket indicated by the numeral 3 into which

is removably fitted the threaded end 4 of the handle of the razor which is indicated by the numeral 5 and which may be of any suitable length and form. The longitudinal edges of the body 1 are provided with teeth indicated by the numeral 6 as is customary in razors of this type but the razor embodying the present invention differs from the ordinary razor in the respect that the end teeth of each series are formed relatively wide and these teeth, which are indicated by the numeral 7, at their base are provided each with a shoulder indicated by the numeral 8, the purpose of which will be presently explained, although it may be stated at this point that the 60 ends of the head 1 between the said shoulders 8 are arcuate and beveled as indicated by the numeral 9, the bevels being inclined in the direction of the convex face 2 of the said head. Also for a purpose to be presently explained, the head 1 is formed in its under side at one end with a seat which is indicated by the numeral 10 and which opens at the end edge of the said body and extends inwardly a short distance from the 65 said edge.

The cap plate of the razor is indicated in general by the numeral 11 and is preferably, although not necessarily, provided with a convex upper surface. The under surface 85 of the cap plate, however, is concave between the lateral edges thereof, as indicated at 12, the curvature corresponding to the curvature of the convex face 2 of the head 1.

The body 1 is provided at each end with a transverse flange which projects from the concave side 12 of the body and the flange at one end of the said body is indicated by the numeral 13 and that at the other end by the numeral 14. Each flange is beveled and transversely curved upon its inner face as indicated at 15 so that when the cap plate is assembled with the head 1, the inner faces of the said flanges will rest snug against the beveled end edges 9 of the head 1. The flange 13 is formed with an inwardly projecting lug 16 which is designed to engage within the seat 10 when the cap is assembled with the head 1 in the manner clearly shown in Figs. 2 and 4 of the drawings, and the engagement of this lug within the seat serves to securely connect the corresponding ends of the head and cap plate in assembled relation. In order that the opposite ends 105 of the said head and cap plate may be simi- 110

larly connected the under face of the body 1 of the head of the razor is formed with a recess 17 and a slot 18 which communicates therewith and within the recess there is arranged a latch plate 19 carrying a finger piece 20 which extends through the slot and by means of which the said latch plate may be shifted into and out of locking engagement in the seat 21 formed in the face 15 of the flange 14. It will now be apparent that the cap plate may be readily assembled with the head by first engaging its end at which the flange 13 is located with the end of the head 1 in which the seat 10 is formed so that the lug 16 will rest within the said seat and that the latch plate 19 may then be shifted so as to securely lock together in assembled relation the other end of the said head and cap plate.

20 The blade of the razor is indicated by the numeral 22 and may be of any of the ordinary thin flexible types now in use and provided preferably with two shaving edges and as will be observed by reference to Figs. 1, 2 and 3 of the drawings, the blade is disposed between the convex face 2 of the head 1 and the concave face 12 of the cap plate 11 and the said cap plate is pressed into engagement with the said head so as to flex the blade and bring the shaving edges thereof in proper relation with respect to the teeth 6. In order that the blade 22 may be held in proper position the same is formed with openings 23 and the cap plate 11 is formed upon its concave face with studs 24 which project through the said openings and into sockets 25 in the convex face 2 of the head 1 in the manner clearly shown in Fig. 2 of the drawings. It is to be noted at this point that when the cap plate is assembled with the head the ends of the flanges 13 and 14 of the cap plate will seat between the shoulders 8 at the corresponding ends of the head 1 and by reason of such engagement of the parts the two members are held against relative displacement.

In order that the razor may be employed in substantially the same manner as the ordinary razor and that either edge of the blade may be used in shaving, each of the flanges 13 and 14 is formed with a threaded socket 26 to receive the threaded end 4 of

the handle 5 of the razor, as shown in dotted lines in Fig. 1 of the drawings.

In order that the latch 19 may be projected into engaging position under normal conditions, a spring 19' is preferably arranged within the recess 17 and bears against the inner end of the said latch.

It will be understood, of course, that while a particular form of handle is illustrated in the drawings, a handle of any other desired form may be employed.

Having thus described the invention, what is claimed as new is:

1. In a razor of the class described, a head having its upper side transversely convex, the ends of the said head being arcuate and beveled in the direction of the upper face of the head, a cap plate disposed upon the upper face of the head and having its underside concave to conform to the convexity of the said face of the head, the cap plate being provided at each end with a flange projecting from the underside thereof, the inner face of each flange being arcuate to conform to the corresponding end of the head, the said face of each flange being further beveled in the direction of its lower edge to snugly fit the bevel of the corresponding end of the head whereby the head is adapted to have wedging reception between the flanges of the said cap plate, and means for securing the head and cap plate together in assembled relation.

2. In a razor of the class described, a head having beveled ends and provided in its under face at one end with a seat, a slideable latch member arranged at the other end of the head and having a portion projecting beyond the beveled edge thereof, a cap plate disposed upon the upper surface of the head and having beveled flanges fitting the said beveled end edges of the head, the flange at one end of the cap plate being provided with a lug engaging in the said seat in the under side of the head and the other flange of the cap plate being provided with a socket to receive the projecting end of the latch member.

In testimony whereof, I affix my signature.

FRANK SCHLATTAU. [L.S.]
